METALLIC FASTENER FOR ENVELOPES

Willard E. Swift, Worcester, Mass., assignor to
United States Envelope Company, Springfield,
Mass., a corporation of Maine

Application April 24, 1931 Serial No. 532,591

5 Claims. (Cl. 229—78)

The invention relates to fasteners for attachment to envelopes. The fasteners are of the type in which a pair of bendable tongues are provided for insertion through a suitable opening in 5 the flap of the envelope and are adapted to be spread apart after insertion through the opening, thereby to seal the flap in closed position. The metallic tongues of fasteners of this type are usually formed integrally with a metallic base 10 portion that provides means for the attachment of the fastener to the rear wall of the envelope. Such fastening means have heretofore consisted of a plurality of single spurs located along the outside edge of the base portion, or, in other cases, 15 a plurality of spurs radiate from a single central opening formed in the base plate.

Fasteners of the above and similar types have been produced and used in tremendous quantities; it has been found that when the tongues are bent 20 upwardly very rapidly in an attempt to secure the envelope flap quickly, the whole fastener is liable to become detached or torn out of the envelope. In the case of fasteners provided with a plurality of single spurs spaced around the edge 25 of the base portion, each spur holds but a small area of paper and may therefore readily be torn out. In the case of fasteners provided with a plurality of spurs radiating from a single hole, it will be seen that owing to the location of all the 30 attaching means within a small area the paper is unable to withstand the excessive leverage imparted by the bending of the tongues and therefore is readily torn.

According to the present invention the fastener 35 is provided with a plurality of separate attaching means which are so arranged in the base that each provides a comparatively large clamping area, and which at the same time are spaced substantial distances apart so that the attaching 40 means cover a sufficient area to prevent excessive leverage on the paper which would tear the fastener from the paper. In this construction the arrangement of the fastening means is such that the area of the base portion is not increased and in 45 certain cases is decreased without diminishing the clamping area of the securing means, thereby providing a fastener having the above advantages without the use of any additional material.

Other advantages will more fully appear from the following description, taken in connection with the accompanying drawing, in which:

Fig. 1 is a plan view of a portion of an envelope showing the novel fastener in position thereon with the sealing flap in open position.

Fig. 2 is a cross-sectional view on the line 2—2 of Fig. 1.

Fig. 3 is an enlarged plan view of a fastener constructed according to the invention.

Fig. 4 is a cross-sectional view on the line 4—4 of Fig. 3.

Fig. 5 is a view of the inside of a portion of an envelope showing the attaching prongs.

Like reference characters refer to like parts throughout the drawing.

Referring first to Figs. 1 and 2, an envelope 1, in connection with which fasteners of this general type are usually employed, comprises, among other things, a rear wall composed of flaps 2 and 3, which overlap each other, as here shown the flap 3 is outermost. Metallic fasteners are usually attached, as shown, to the rear wall in the overlapping portion of the flaps to secure both flaps together. The envelope also provides a front wall 4 having a closure flap 5 at the upper end thereof; said closure flap provides a reinforced opening 6 through which the tongues of the fastener are inserted in order to seal the envelope.

Referring now to Figs. 1 to 4, inclusive, the fastener of the invention is formed from sheet metal and comprises a pair of tongues 7 and 8 extending from opposite sides of a central body portion 10. The tongues 7 and 8 are preferably of different lengths to permit ready spreading of the tongues in securing the flap of an envelope in position.

The body portion 10 in the form of the invention shown comprises a pair of substantially triangular portions 11 and 12 integral with and extending on opposite sides of the tongues 7 and 8, the apexes of the triangles being located substantially on the center line of the tongues 7 and 8, and corresponding sides of opposite triangles extending substantially along the same line. Each triangular portion of the base 10 is provided with a pair of attaching prongs 13 which are integral with the fastener and which are formed by forcing a die through the metal of the fastener, to bend said prongs substantially at right angles to the base, with the line of attachment of each of the prongs 13 to the base extending on a line substantially parallel with the corresponding converging side of one of the triangular portions. Each of the prongs 13 is generally triangular in shape and is formed from the base as the die passes through said base; said die provides intersecting slits 14 and 15 for each prong, in the material of the base 10. Slits 14 are parallel to the center line of the tongue, and

spaced from the outer edge of the base portion to provide a web 16 parallel to the center line of the tongues on each side of said center line, and corresponding slits 15 for opposite prongs 13 in one of the triangular portions are spaced apart to provide in the base a central web 17 extending radially outwardly from the center of the base to the web 16. The material between the lines of attachment of the prongs and the edges 10 of the triangular portions provide diagonally extending webs 18, extending outwardly from the center of the base portion substantially midway between the webs 17 and the tongues, and the outer ends of the webs are integral with the ends of the webs 16. Each of the prongs 13, which is attached integrally along one longitudinal edge of one of the webs 18 is arranged to be folded over against said web when the fastener is secured to the envelope, and the web is accordingly 15 preferably at least as wide as the length of the prong to provide a clamping surface for the entire area of the prong. This arrangement, by reason of the structure of the prongs provides a relatively large clamping area for each prong. 20 A curved edge 20 connects each converging edge of the triangular portions with the corresponding edge of the tongue to avoid extreme localization of the bending action between the tongue and the base.

30 The base portion accordingly comprises a plurality of webs 17 and 18 extending radially from the center of the base on opposite sides of the center line of the tongues 7 and 8, the webs on opposite sides being integrally connected together at their outer end by webs 16. The material between the webs provides attaching prongs, each of which is integrally attached to one longitudinal edge of one of the webs, said web being at least as wide as the length of the prong. 35 From a consideration of Figs. 3 and 4 it will be seen that the lines of attachment of two of the prongs is at right angles to the line of attachment of the other two, and that each line of attachment extends diagonally to the center line of the tongues, that is, on a line oblique to said center line. By such arrangement of the tongues, a wider prong may be provided in a base of a given size than would be provided by forming the prong parallel to or perpendicular to the center line of the tongues. Furthermore such formation permits the clamping areas to be located a substantial distance from the center of the base, whereby a secure attachment to the envelope is obtained.

45 The prongs in the position of Figs. 3 and 4 are readily inserted through the overlapping portion of the flaps 2 and 3, after which they are bent against the inner side of the envelope and the material of the envelope is clamped between said prong and the webs 18, to provide a secure clamping action. As the diagonally opposite prongs are bent in opposite directions, as shown in Fig. 5, the fastener is securely held against rocking movement in any direction.

50 In the usual envelope construction, the grain or fiber of the paper runs in a direction substantially perpendicular to the opening; in the construction of Fig. 1, perpendicular to the center line of tongues 7 and 8. It will be apparent that the prongs 13 are inserted through the envelope flaps 2 and 3 on lines transverse or oblique to the direction of the fibers, thereby providing a securely attached fastener, since, by reason of this transverse attachment, there is less tendency to split the paper along the grain when the paper

is put under strain, than in fasteners in which the prongs are inserted parallel to the grain. It will be further apparent that the transverse attachment is such that the tongues of the present type of fastener may be bent for insertion through the flap opening with very little possibility of the fastener pulling out of the paper. Moreover, by the particular arrangement of prongs in the present fastener certain of the prongs 13 will always extend transverse or oblique to the direction of the grain of the paper, whatever the direction of the grain, when the paper has been formed into an envelope.

I claim,

1. A metallic fastener for envelopes comprising a base portion for attachment to an envelope wall, said base portion providing a pair of laterally and oppositely projecting integral tongues adapted for insertion through an opening of the envelope flap, said base member having a plurality of radial webs extending from the center thereof on each side of the tongues, a portion of the material between certain of said webs being bent at right angles to the plane of the base to form prongs, each of the latter being integrally connected to a radial edge of one of the webs, the radial webs on opposite sides of the tongues being connected at their outer edges. 65

2. A metallic fastener for envelopes comprising a base portion for attachment to an envelope wall, 75 said base portion providing a pair of laterally and oppositely projecting integral tongues adapted for insertion through an opening of the envelope flap, said base member having a plurality of radial webs extending out from the central portion 80 of the base on each side of the center line of the tongues, certain of the material between said webs being bent to form triangular prongs, each prong being integrally connected to a longitudinal radial edge of one of said webs, the webs to which 85 said prongs are integrally connected being substantially equal in width to the length of the prong.

3. A metallic fastener for envelopes comprising a base portion for attachment to an envelope wall, 90 said base portion providing a pair of laterally and oppositely projecting integral tongues adapted for insertion through an opening of the envelope flap, a plurality of triangular prongs integrally formed from the material of the base portion, the line of attachment for each prong being radial with reference to the center of the base portion, said prongs being formed by intersecting slits at right angles, said slits extending parallel and perpendicular to said tongues, the material between the slits being bent downwardly to form said prong, the portion of the base between the point of attachment of each prong and the edge of the base, against which portion said prong is arranged to be clamped, being substantially equal 100 in width to the length of said prong. 105

4. A metallic fastener for envelopes of paper or the like, comprising a base portion for attachment to an envelope wall, said base portion providing integral tongues for insertion through an opening in the envelope flap, a plurality of prongs integrally formed with the material of the base portion, said prongs having radial lines of attachment to the base, the line of attachment of certain of said prongs to the base being substantially perpendicular to the line of attachment of the remaining prongs, whereby, when said fastener is attached to the envelope, certain of the prongs will be projected through the material of 110 115 120

the envelope on a line transverse to the direction of the fibers of the envelope material.

5. A metallic fastener for envelopes comprising a base portion for attachment to an envelope wall, 5 said base portion providing a pair of laterally and oppositely projecting integral tongues adapted for insertion through an opening of the envelope flap, and a plurality of prongs integrally formed from said base portion, each prong being formed by

intersecting slits in said base portion substantially at right angles to each other, with the material between said slits bent out of the plane of the base to form said prong, the lines of attachment of the prongs to the base portion being radial with reference to the center of the base portion.
